UNITED STATES PATENT OFFICE.

GEORGE DE WITT, OF GLOVERSVILLE, NEW YORK.

UMBRELLA STAND.

Application filed February 8, 1923. Serial No. 617,830.

To all whom it may concern:

Be it known that I, GEORGE DE WITT, a citizen of the United States, and a resident of Gloversville, in the county of Fulton and State of New York, have invented a new and Improved Umbrella Stand, of which the following is a full, clear, and exact description.

The present invention relates to new and useful improvements in articles of furniture, and it pertains more particularly to a device of this character in the form of a combined umbrella and rubber stand.

It is one of the objects of the present invention to provide an umbrella stand in which a plurality of umbrellas may be placed, said stand being so constructed as to provide a separate compartment for each umbrella.

It is a further object of the invention to provide a separate rack or recess for rubbers and the like.

It is a still further object of the invention to provide means for catching the drain water from both the umbrellas and the rubbers.

With the above and other objects in view, reference is had to the accompanying drawings, in which—

Figure 1 is a view in front elevation of a combined rubber and umbrella rack constructed in accordance with the present invention;

Fig. 2 is a longitudinal vertical sectional view thereof;

Fig. 3 is a transverse vertical sectional view of the device taken on the line 3—3 of Fig. 1.

Referring more particularly to the drawings, the device comprises corner posts 5, of which there are four, connected together by upper longitudinally extending bars or the like, 6, and transversely extending longitudinal bars or the like, 7. Secured to the corner posts 5, intermediate of their ends, is a partition 8, and such partition has its upper face formed with a recessed portion in the nature of inclined walls 9. Interposed between this partition 8 and the longitudinally extending bars 6, are slats or the like, 10. Dividing the space above the partition 9, into a plurality of compartments, are vertically disposed partitions 11, which are

adapted to provide a plurality of individual compartments for the reception of umbrellas.

It will be noted that the end partitions 11 rest upon the horizontal partition 8, the central partitions, however, being spaced with respect thereto to provide space for the free flow of water draining from the umbrellas. Located below the partition 8, is a partition 12, which latter partition has a depressed portion 13 in the form of inclined walls, which depressed portion is provided with an opening 14 forming a drain. Leading from the partition 8 to a point above the drain opening 14 of the partition 12, is a drain spout 15, which serves to convey the water from the recessed portion 9 of the partition 8 to the drain opening 14.

Mounted within the partition 12 is a plurality of slats or the like, 16, which serve to support rubber-shoes and the like upon the partition 12.

Slidably mounted in guides or cleats 17, is a receptacle 18, which is adapted to receive the drain water from the drain opening 14. The partition 12 is provided on its lower face with a stop 19 which serves to limit the movement of the receptacle 18, and the receptacle 18 is provided with a handle 20 by means of which it is moved to and from position on the under face of the partition 12. The partition 12 is provided on its upper face with guard rails or the like, 21, to prevent accidental displacement of the rubbers with respect to the slats 16.

From the foregoing it is apparent that the present invention provides a new and improved article of furniture which serves to carry a plurality of umbrellas in individual compartments and that the water draining from such umbrellas is amply taken up by the drain to the receptacle 18. Furthermore, the invention provides means for supporting a plurality of rubber-shoes or the like, in such a manner that the drain water therefrom will be carried off to the receptacle 18.

What is claimed is:

A device of the character described comprising a plurality of corner posts, a horizontal partition securing said corner posts together, means for dividing the space above

said partition into a plurality of umbrella-receiving compartments, a second partition arranged below said first-mentioned partition and serving as a rack for rubber-shoes and the like, a water receptacle removably carried by the under face of said last-mentioned partition, an opening formed in said

last-mentioned partition and a pipe leading from said first-mentioned partition and disposed directly over said opening for conveying the drip water from each of said partitions to said receptacle. ¹⁰

GEORGE DE WITT.
